UNITED STATES PATENT OFFICE.

ANDREW A. HENDERSON, OF PORTSMOUTH, NEW HAMPSHIRE.

CALORIC ENGINE.

Specification of Letters Patent No. 30,315, dated October 9, 1860.

To all whom it may concern:

Be it known that I, A. A. HENDERSON, of Portsmouth, in the county of Rockingham and State of New Hampshire, have invented 5 certain new and useful Improvements in Caloric Engines; and I do hereby declare that the following is a full, clear, and exact description of the same, reference being had to the accompanying drawing, making a part 10 of this specification, in which—

Figure 1 represents a longitudinal vertical section of my invention taken in the plane indicated by the line x, x , Fig. 3, and looking in the direction of the arrow marked opposite site to that line. Fig. 2 is a similar section taken in the plane indicated by the line y, y , Fig. 3, and looking in the direction of the arrow marked opposite to that line. Fig. 3 is a plan or top view of the invention. Fig. 4 is a side elevation of the supply piston detached. Fig. 5 is a front elevation of the same.

Similar letters of reference indicate corresponding parts in the several figures.

This invention consists, 1st, in the arrangement of a flame space between the supply cylinder and the working cylinder, whereby a more intense and quicker heating of the air in said cylinders is effected; 2nd, 25 the arrangement of an eccentric frame suspended from a suitable pivot and operated by an eccentric in such manner that the supply piston receives the desired motion in advance of the working piston and that a reversing of the engine is rendered possible; 3rd, the combination with the supply piston of the regenerator in such a manner that both move together and that the air in passing from one side of the piston to the other, 40 is compelled to pass through said regenerator where it takes up the heat stored up therein, so that when it arrives in the center of heat it takes but little time to heat it to the desired temperature; 4th, in the arrangement 45 of a reversible eccentric in combination with a spring bar for the purpose of opening and closing the exhaust valve instantaneously as the crank passes its centers.

To enable those skilled in the art to make 50 and use my invention I will proceed to describe its construction and operation with reference to the drawing.

Two cylinders A, and G, with spherical bottoms are cast together leaving between 55 them a space a^* , for the flame to pass between. The working cylinder A, which is on

the top, is open at one end and the lower or supply cylinder G, is provided with a head and stuffing box L. A spring valve M, opens inward on the head of the cylinder G, 60 and both cylinders communicate with each other by the port U. The capacity of both cylinders may be equal, but by making the supply cylinder greater, an increase of power may be obtained.

The working cylinder is placed above and at one side to allow room for the eccentric N, in a vertical line with the center of the lower cylinder. The spherical ends of the two cylinders are inclosed in a furnace S, 70 from which the smoke is carried off by a pipe T.

The supply cylinder G, has on its upper side outside of the furnace a valve box R, inclosing the exhaust valve b, which opens 75 inward. Motion is imparted to this valve from an eccentric X, on the main shaft, through the rod c. This eccentric is loose on the shaft being secured by a catch for reversing, and it operates against the inclined 80 planes on the spring rod d, in such a manner that the valve opened by the eccentric is closed by the spring.

The pistons of both cylinders are alike in general form those parts of the same which 85 enter the furnace ends of the cylinders being prolonged with spherical extremities so that the rubbing surfaces are removed from the effect of high heat.

The working piston B, is united by a connecting rod C, to a crank D, on the shaft E, which bears a fly wheel F. This piston is cast in two pieces united by screw bolts. A hollow cylindrical part B', fitting the cylinder has bolted against its outer open end a 90 ring B², and between them is formed the recess B³, which receives the packing of the piston. This packing must of course be made of metal. The part B', is cast with a diaphragm B⁴, dividing it into a closed 100 chamber B⁵, (occupying that part of the piston which enters the furnace) and an open space B⁶. The rod C, is in direct connection with the piston by a center fixed in the diaphragm B⁴, (similar to a trunk engine) and it vibrates in the open space B⁶. By this arrangement the packing of the piston is removed from the center of heat and the conducted heat is to a certain extent 105 carried off and moderated through the access of cold air to the walls of the space B⁶.

The piston J, of the supply cylinder has a

piston rod H, passing through the stuffing box L, and its outer extremity works in a guide K.

On the shaft E, over the center of the supply cylinder G, is an eccentric N, which acts on an eccentric frame or strip P, suspended from a center e, above said shaft. This center is fixed in the end of an arm O, bolted to the cylinder A. The eccentric N, is loose on the shaft (with a catch) for reversing. An arm P', extends from the eccentric frame P, down to the piston rod H, with which it is connected by the stirrup I. This stirrup can be disconnected from the piston rod and the latter may be moved by a hand lever, which may be necessary for the purpose of starting the engine.

The eccentric frame P, receives a pendulum motion by the action of the eccentric N, against the upper and lower surfaces and it is so arranged, that its throw in one direction occurs in one twelfth of a revolution and its throw in the other direction occupies one fourth of a revolution of the shaft E. The motion of this frame, which is communicated to the piston J, governs the transfer of cold air from the outer to the inner or furnace end of the supply cylinder, as will be presently more fully explained, and as the power of the engine will be increased the more rapidly this transfer can be made relatively to the stroke of the working piston, it follows, that the engine will work with more power in one direction than in the other. This direction is indicated by the arrows marked on the crank in Figs. 1, and 2, and on the fly wheel in Fig. 3.

The supply piston J, is cast in two pieces, the prolonged piece J, and the piston head J'. The piece J, forms a hollow cylinder closed at its furnace end and open at the other against which the piston head is bolted. The body of the cylinder J, is of less diameter than the bore of the supply cylinder, so as to leave a space f, for the passage of air between the two, but its furnace end is extended by a disk J², which fits the cylinder, and the transit of air from the space f, to the furnace end of the cylinder takes place through a recess J³, and by holes g, passing from the bottom of said recess through the disk J². This recess is fitted with wire gauze closely packed or with any other suitable fibrous material kept in place by a ring Q. Thus packed the recess J³, forms a regenerator through which the air must pass both in supply and exhaust. The piston head J', which also fits closely into the cylinder G, is secured to the body J, by means of screws or in any other convenient manner, and close behind this head is the recess J⁴, which serves to receive the ring W. This ring acts both as valve and as packing, and the recess J⁴, has sufficient

width and depth to allow the ring W, to recede from the piston head and to bear against projections J⁵, on the inner surface of the recess, and in this position a passage for air under or inside of the ring or valve W, is open. The piston head is pierced with a series of holes j, at its margin which are closed when the valve W, comes against it. This valve is a ring cut and tongued and made to bear by its elasticity against the inner surface of the cylinder and therefore as the piston moves in, it is brought against the piston head from which it recedes as the piston moves out. The course taken by the air is shown by the arrows in Fig. 2.

The operation is as follows. The engine is single acting and it has most power when the revolution is in the direction of the arrows marked on the crank in Figs. 1, and 2, and on the fly wheel in Fig. 3, as above stated. If both pistons are at the inner or furnace end of the cylinders, when the engine stops, a small motion imparted to the supply piston either by turning the fly wheel or by means of a starting bar, will be sufficient to remove the valve W, from the piston head J', and the cold air which has entered into the supply cylinder through the valve M, during the return stroke of the piston, will rush through the passage in the piston J, and through the regenerator to the furnace end of the cylinder. By thus being brought in contact with the hot walls of the supply cylinder the air expands and it rushes through the opening U, into the working cylinder causing the working piston to move in the direction of the arrow marked near it in Fig. 1. By this motion of the working piston the crank shaft is caused to rotate and the eccentric N, by coming in contact with the inner surface of the eccentric frame P, causes the supply piston to move suddenly to the outer end of its stroke whereby a large quantity of cold air is admitted to the furnace end of the supply cylinder and through the action of this air as it expands through the influence of the heated walls of both cylinders, the working piston is enabled to finish its stroke. From this it will be understood that the sooner the stroke of the supply piston is completed as compared with the stroke of the working piston, the greater will be the power of the engine. The return stroke is accomplished by the action of the fly wheel and as soon as the crank has passed its outer center, the exhaust valve is opened by the action of the eccentric X, and the hot air contained in both cylinders is allowed to pass through the regenerator and through the passage in the supply piston J, out into the open atmosphere. In passing through the regenerator the air deposits a portion of its caloric which on the next succeeding stroke is absorbed by the cold air rushing in through

the valve M, and through the passage in the piston J. At the same time by causing the supply piston to accomplish its stroke in a fractional part of the working piston, the former is allowed to remain stationary in the furnace end of the supply cylinder the same as in its outer end, and during the time it thus remains in the furnace end, the regenerator and all the adjoining parts are heated to a high temperature, and as the crank passes the inner center, the exhaust valve closes and the action of the pistons commences again as above described and the cold air in passing through the regenerator is heated to such a degree, that its action on the working piston takes place instantaneously as it enters the furnace ends of the cylinders.

For the purpose of reversing the engine all that is necessary is to reverse the eccentric N, and X, and to start the engine in the opposite direction and it will be easily understood that the eccentric frame P, may be so arranged that the throw of the supply piston in either direction will be accomplished during the same portion of the stroke of the working piston and in this case the power of the engine in either direction would be the same. In this case it is likely that the stroke of the supply piston in one eighth of a revolution will be best adapted for practical purposes. In order to stop the engine the stirrup I, or the exhaust valve is disconnected. The power obtained by this engine will be equal to about 4 or 5 pounds pressure per square inch with a temperature of 491° Fahr., and by increasing the relative capacity of the supply cylinder and by attaining higher temperatures the power may be

still further increased. By this arrangement of the cylinders and of the exhaust valve all back pressure is avoided and by having the ends of both cylinders inclosed in the furnace with a flame space between them the fire surface is considerably increased. The air as it passes into the furnace ends of the cylinders, is nearer to the center of the heat than in other air engines and by giving to the supply piston a period of rest in the furnace it acquires heat during its rest. The capacity of the supply cylinder may be increased at pleasure, and by connecting the working piston directly to the crank, the length of the working cylinder may be reduced.

Having thus fully described my invention what I claim as new and desire to secure by Letters Patent is—

1. The arrangement of the flame space a^* , between the cylinders A, and G, substantially as and for the purpose set forth.
2. The arrangement of an eccentric frame P, and reversible eccentric N, in combination with the supply piston J, constructed and operating substantially as and for the purpose specified.
3. The combination of the regenerator J³, with the supply piston J, constructed and operating substantially as and for the purpose described.
4. The arrangement of the reversible eccentric X, in combination with the spring rod d, and exhaust valve b, constructed and operating in the manner and for the purpose set forth.

ANDREW A. HENDERSON.
